UNITED STATES PATENT OFFICE

2,254,425

CRUSHER

Arthur W. Fahrenwald, Moscow, Idaho.

Application May 28, 1938, Serial No. 210,615

3 Claims. (Cl. 83—10)

The primary object of the invention is to improve crushers of this type in certain respects to insure a simple construction, stability and durability of parts, and smooth operation of the gyratory crushing unit. An adit zone for coarse material and an exit zone for the finer material are provided between the gyratory head and the stationary concave, and means are provided for accurately and conveniently adjusting the concave with relation to the gyratory head, in order that the crushing capacity of the adit zone and that of the exit zone may be equalized to insure uniform feed and passage of the material through the crushing mill.

To insure a maximum degree of stability for the floating gyratory unit a long bearing extending substantially the length of the central spindle is provided and in which the eccentric sleeve is journaled with the spindle, and the latter is laterally braced and supported so that the gyratory head may have an effective rolling contact with the material to be crushed.

Due to the combination and arrangement of parts of the gyrating unit means are provided for freely lubricating the parts against wear and for constantly circulating the lubricant or oil in contact with the bearings of working parts.

The invention consists in certain novel combinations and arrangements of parts as will herein-after be more fully set forth and claimed. In the accompanying drawing I have illustrated one complete example of the physical embodiment of my invention wherein the parts are combined and arranged according to one mode I have thus far devised for the practical application of the principles of my invention. It will be understood that changes and alterations may be made in these exemplifying structures, within the scope of my appended claims, without departing from the principles of my invention.

Figure 1 is a vertical sectional view of a crushing mill embodying my invention.

Figure 2 is a view in side elevation of the gyratory crusher with its integral spindle and floating base plate or disk.

Figure 3 is a horizontal sectional view through the frame of the machine, the bearing sleeve, the eccentric bushing and the spindle, and showing also the driving gears for the eccentric bushing.

In the assembly view Figure 1 it will be seen that the base 1 is fashioned with an integral upright cylindrical frame 2, and an inner, concentrically spaced shell 3, and in Figure 3 spaces 4, 5, are provided between the frame and the shell for the discharge of the crushed material. At the upper end of the cylindrical frame, a cylindrical head 5 is provided, and this head is threaded at 5' on the exterior of the cylindrical frame 2 to an approximate adjustment for the frame

and the frame-head. The frame-head is accurately and precisely adjusted on the frame through the use of a series of adjusting bolts 6 that are threaded through bolt holes in the annular top flange 6' of the frame-head, with their lower ends bearing on the top edge of the frame 2. Through the use of the threads 5' and the adjusting bolts 6, the frame-head is properly adjusted, and then the bolts 6 are locked in place by means of lock nuts 7 on the bolts turned up tight against the bottom face of the flange 6'.

The frame-head is also provided with an inner annular flange 8 depending within the frame-head and spaced concentrically therewith, and this depending flange is fashioned with a tapered face to receive the concave 9 which forms the stationary jaw of the crusher. As indicated in Figure 1 the concave is fashioned with an upper tapered sloping face 10 and a lower outwardly flaring tapered slope 11, and these sloping faces or stationary jaws, together with the gyratory crushing head, form an adit zone for the reception of coarse material, and an exit zone for the discharge of the crushed or finer material, the coarse material being fed to the adit zone through a circular collar 12 that projects upwardly from the concave and co-acts with a suitable hopper for feeding the material to the mill.

The concave is adjusted and rigidly suspended in the frame-head, and it is retained in place through means that are readily accessible and may be manipulated with facility. For this purpose a series of holes 13 are provided in the collar 12 of the concave, and radial locking levers 14 are disposed about the concave with their inner ends protruding into or through the holes. The levers are supported on fulcrums 15 located on the top edge of the flange 8 of the frame-head, and vertical locking bolts 16 are passed through holes in the flange 8 and complementary holes in the outer ends of the levers. The bolts are entered up through the flange-holes with their heads 17 bearing against the under face of the flange, and tightening or lock nuts 18 are threaded on the ends of the bolts as they protrude through the lever holes. Thus by turning home the nuts on the bolts, the concave is drawn up into position in the flange 8 and rigidly seated in position for use. Repairs or replacements may readily be made, and parts may with facility be removed for repairs or replacements, by loosening the nuts and withdrawing the supporting levers.

The floating gyratory unit is mounted centrally of and below the concave, and as seen in Figures 2 and 3, the frusto-conical crusher-head 19 is fashioned with an integral spindle having two journals 20 and 21 of differing diameters, the 60 heavier or larger journal 20 integral with the

head, and the other journal being materially reduced in diameter. On the face of the frustoconical head is mounted a complementary wear-mantle 22 secured to the head by means of a crown-bolt 23, and the working face of the mantle is stepped to form concentric annular bands as 24, and steps between the bands. The crusher head has a rolling contact with the material in the adit and exit zones, and these steps retard the downward movement of the material to prevent choking in both the adit zone and the exit zone. Thus the coarse material fed to the adit zone is successively crushed to a finer size as it passes through the two zones, and the fines eventually are discharged through the vertical channels or spaces 4 of the frame.

At its lower end the spindle is provided with a floating foot-plate or disk 25 having a socket 26 mounted on a reduced end 27 of the spindle as shown in dotted lines. The disk is fashioned with a semi-spherical lower face, the curve of which is struck from a center located above the crown of the gyratory crushing head, and this face rides or gyrates with a floating movement over a complementary concave face in the base or bearing plate 28 that is located at the bottom of the main frame and bolted at 29 to the base 1 of the frame.

The locus of radii of the spherical thrust bearing may coincide with the center of gyration or neutral point of the spindle and it may or may not be at the apex of the gyrating cone. That is, it may be somewhat above or below this point but generally it should be nearly on the apex of said cone.

The spindle is supported in a bearing sleeve 30 having a lateral flange 31 that is rigidly bolted on the top edge of the shell 2, and a housing 32, exterior of the sleeve is provided with a bottom flange 33 that is seated in a complementary groove in the top face of the flange 31, the housing being designed as a dust-guard to prevent access of dust to the lubricated parts of the gyrating unit.

The housing 32 serves also to collect the lubricating oil pumped up between the bearing sleeve 30 and 34 and between 34 and the spindle housing 32 and serves to catch the oil thus pumped and return it through ports opening into the oil well 49.

Within the bearing sleeve is journaled a rotary bushing 34 having two eccentric bores 35 and 36 complementary to the two diameters of the spindle that is encased by the bushing, and a usual liner 37 is interposed between the bushing and the bearing sleeve.

At its lower end, just below the lower end of the bearing sleeve, the bushing is fashioned with an exterior flange 38 which is bolted to a horizontally disposed gearing or gear ring 39, and this ring rests upon a bearing plate or gasket 40 that is seated on the bottom bearing ring 41 that supports the bearing member or bushing of the spindle. The bottom bearing 41, as shown is bolted to the base of the frame by bolts 29, and this bearing ring, which overhangs the floating base plate or disk 25, forms a support at the lower end for the eccentric bushing, with the spindle free to revolve or rotate in the bushing as it partakes of the gyratory movement created by the rotating eccentric bushing.

The driving mechanism for the crusher includes a pinion 42 in mesh with the gear ring 39, and a horizontal drive shaft 43 journaled in the frame 1, and supported by a bearing 44, 44 which is mounted in a housing 45 bolted to the frame 1. A pulley 47 on the outer end of the drive shaft is operated by a belt-drive from a suitable source of power to drive the gyratory crusher unit.

this pinion is keyed to the horizontal drive shaft 43 that is journaled in bearings 44, 44 which are mounted in the housing 45 that is bolted to the flange 46 of the main frame. A pulley 47 on the outer end of the drive shaft is operated by a belt-drive from a suitable source of power to drive the gyratory crusher unit.

Lubricating oil under pressure is supplied through the inlet pipe 48 to the oil well 49 in which the floating disk 25 gyrates, and by means of vertical and lateral oil ducts as 50 the lubricating oil is circulated through and around the journal bearings, and into the oil chamber 51 in which the gear ring and pinion are enclosed. An outlet pipe 52 from the oil chamber 51 disposes of the used oil in suitable manner.

From the above description taken in connection with the drawing the construction and operation of the crusher will be apparent, and the advantages of the compactly arranged, easily adjusted parts, together with the lateral bracing of the gyratory unit will also be clear.

Having thus fully described my invention, what I claim as new and desire to secure by Letters Patent is:

1. In a crushing mill, the combination with a main frame having an inner shell, and an upright bearing sleeve mounted on and projecting above and below the top of the shell, of a rotary bushing mounted and extending the full length of the sleeve, said bushing having two bores of differing diameters eccentrically arranged therein, a spindle journaled in the eccentric bores, and having a crushing head integral therewith, a spherical convex bearing disc mounted on the lower end of the spindle, and having a center of curvature adjacent the neutral point of the spindle and above the crushing head, a bearing support for the disc, and means for revolving the bushing.

2. In a crushing mill, the combination of a main frame, an inner frame shell having a supporting flange, a centrally disposed bearing sleeve having an exterior flange mounted on said supporting flange, a bushing journaled in said sleeve and having an eccentric bore, means for revolving the bushing, a spindle journaled in the eccentric bore of the bushing and having a crushing head therewith, a bearing support for the bushing, and a spherical convex lower terminal bearing support for said spindle, the center of curvature of the convex bearing support being adjacent the neutral point of the spindle and above the crushing head.

3. In a crushing mill, the combination of a main frame having a central upright bearing sleeve, a bushing having an eccentric bore and journaled in said sleeve, said bushing having a ring gear rigid with its lower end below the sleeve, a bearing ring mounted in the frame to support said ring gear, a drive pinion engaging said ring gear and including means for rotating same, a spindle journaled in the eccentric bore and having a crushing head integral therewith, a spherical convex bearing disc mounted on the lower end of the spindle and having a center of curvature adjacent the neutral point of the spindle and above the crushing head, and a complementary spherical concave bearing support for said disc.

ARTHUR W. FAHRENWALD.
